UNITED STATES PATENT OFFICE.

EDWARD H. BELDEN, OF TOLEDO, OHIO, ASSIGNOR TO THE WILLYS-OVERLAND COMPANY, OF TOLEDO, OHIO, A CORPORATION OF OHIO.

INTERNAL-COMBUSTION ENGINE.

Application filed March 5, 1921. Serial No. 449,715.

My invention relates to internal combustion engines and has for its object to provide an improved crank shaft and bearing arrangement for the same in engines of this 5 type.

Another object of the invention is to provide an improved bearing arrangement and drive mechanism for the eccentric shaft of a sleeve valve engine.

10 Another object of the invention is to provide an improved crank and eccentric shaft mounting for multi-cylinder engines whereby the vibration or "whipping" tendency in the shaft is reduced to a minimum.

15 Another object of the invention is to provide an engine constructed in an improved manner to permit a number of the operating units thereof to be driven by the crank shaft from a point intermediate its ends.

20 Another object of the invention is to provide an improved drive mechanism constructed in a manner to be interchangeably connected with different classes of operating units for controlling a motor driven vehicle.

25 Another object of the invention is to provide an improved forced feed oiling system for internal combustion engines.

With these and other objects in view, the invention comprises certain improved forms 30 of construction, arrangement of parts, and combination of elements which will be hereinafter more fully described and claimed, it being understood that the present showing is intended to illustrate one form of the invention, which is susceptible of various 35 modifications to suit special or varying conditions, and it will be further understood that the terms which I have used are merely descriptive and not limiting, and that it is my intention to include any and all modifications which come within the scope of the 40 invention as defined by the appended claims.

In the accompanying drawings I have illustrated one embodiment of the invention 45 in which:

Figure I is a longitudinal sectional elevation of an engine embodying the invention.

Figure II is a transverse section taken on line II—II of Figure I.

50 Figure III is a transverse sectional elevation taken on line III—III of Figure I.

Figure IV is an enlarged transverse section taken on line IV—IV of Figure I.

55 Figure V is a detail sectional view taken on line V—V of Figure IV.

Figure VI is a side elevation of the portion of the engine base illustrated in Figure IV showing by dotted lines and in more or less conventional form the drive for the generator and distributor.

60 Referring to the drawings 10 and 11 represent the upper and lower sections respectively of the crank case of the engine which are suitably bolted-together and which serve to support the cylinders 12 having the heads 13 projecting therein, the heads being provided with upwardly extending tubular portions 14 for receiving the spark plugs 15, said tubular portions extending through the removable cover 16 and being threaded to 70 receive the retaining nuts 17 by means of which the cover is clamped upon the cylinders. The cylinders and heads are surrounded by a cooling chamber as indicated at 18. The intake manifold 19 is adapted to communicate with the carburetor 20 by means of the transverse pipe 21 extending centrally through the engine as indicated in Figure I, while the exhaust manifold 22 is on the same side with the carburetor as indicated 75 in Figure II. The inner and outer sleeve valves 23 and 24 respectively, operate within the cylinder, while the piston 25 and connecting rod 26 move within the inner sleeve valve, said inner and outer sleeves being 80 actuated by the connecting rods 27 and 28, respectively, which are connected in the usual manner with the eccentric shaft 29, which is in turn driven by the crank shaft 85 30 in a manner to be presently described. 90 The upper and lower sections 10 and 11 of the crank case are preferably divided at the center of the crank shaft and the upper section is provided with the front and rear end walls 31 and 32 respectively, in which 95 are formed the upper halves of the front and rear crank shaft bearings 33 and 34, the lower halves of the bearings being bolted on or otherwise secured to the crank case. The front and rear bearings 35 and 36 on the 100 opposite ends of the eccentric shaft 29 are also formed in the crank case walls as shown in Figure I. At a point substantially central of the crank case are the vertical transverse connecting walls 37 and 39 which in 105 turn are connected by the horizontal wall 38 as shown in Figure I. The walls 37 and 38 are provided with the crank shaft bearings 40 and 41 respectively, the lower halves of which are removable and said walls are 110

also provided with the eccentric shaft bearings 42 and 43 respectively. Thus the relatively long crank and eccentric shafts required for an engine having six or a greater number of cylinders are supported at points immediately on the opposite sides of their centers, as well as at their ends, whereby the possibility of the "whipping" or excessive vibration of these shafts is prevented. This is an important feature of applicant's invention and serves to greatly increase the efficiency of the engine by affording an extremely well balanced driving mechanism which is free from the excessive strains and stresses usually found in engines of this type. Another important feature of the invention comprises the driving of the eccentric shaft from the center of the crank shaft and likewise the driving of the several operating units for controlling the engine from the same point in a manner which will be hereinafter explained.

It will be seen from Figure I that the crank shaft is provided at its center and intermediate the centrally disposed bearings 40 and 41 with gears or sprockets 44 and 45 which are preferably formed integral with the shaft, but which may be separately formed and secured thereon if desired. Engaging the sprocket 45 is the chain 46 which extends over a sprocket 47 on a short shaft 48 carrying a gear 49 meshing with a worm 50 for operating the oil or lubricating pump 51 to force the lubricant from the bottom of the crank case through the crank shaft in a manner to be presently described, said pump being removable bodily through the bottom of the casing upon removal of the plate 52 shown in the lower left hand corner of Figure III. The shaft 48 is journalled at one end in a removable bracket 53 suitably connected with the extension 54 of the upper section 10 of the crank case, while its opposite end is journalled in the wall of the extension and is connected with and adapted to drive the generator 55 as shown in Figure VI. The outer end of the shaft 48, supported by the removable bracket 53, is provided with a gear 56 adapted to drive the distributor 57 through a gear on the distributor shaft, (not shown). If it is found desirable to use a magneto, the bracket 53 and distributor 57 are removed and a specially designed bracket carrying the magneto is applied in a manner to permit the magneto to be driven by the shaft 48. In this way the generator, the distributor or the magneto, is driven directly from the center of the crank shaft from a point between the two center bearings 40 and 41. At the center of the eccentric shaft 29 and at a point opposite the sprocket 44 of the crank shaft 30 is a sprocket 58 driven by a chain 59 connecting said sprockets as shown in Figure III. Secured upon the eccentric shaft ad-

jacent the sprocket 58 is a gear 60 meshing with another gear 61 on the shaft 62 adapted to drive a tire pump 63 mounted on a bracket 64 bolted to the crank case as shown in Figure II, said shaft 62 being suitably journaled in the walls of the removable extension 65 which is bolted to the casing, and which forms a housing for the gear 61. The fly wheel 66 is bolted to the rear end of the crank shaft and is adapted to be driven by the starting motor 67, while the opposite end of the crank shaft is adapted to drive the fan in the usual manner as shown in Figure I.

A water circulating pump (not shown) is adapted to be driven by a shaft 68 having a gear 69 connected with the gear 70 on the front end of the eccentric shaft.

Coming now to the lubricating system of the engine, the pump 51 is adapted to supply lubricating material to the pipe 71 running longitudinally of the engine for the full length thereof and supported by the boss-like portions 72 of the crank shaft casting 10. There are three leads extending from this pipe to the crank shaft, one for each end bearing of the crank shaft and another leading through the transverse wall 38 of the casing directly to the crank shaft bearing 41, said leads being formed as indicated at 73 in Figure III, the same being drilled through the tube-like portions 74 of the casing. The front crank shaft bearing 33 is provided with an inlet opening 75 registering with the passageway 73 leading from the front end of the pipe 71 and from said inlet opening 75 a passageway 76 leads through the crank shaft to the first two connecting rod bearings thereon. The rear crank shaft bearing 34 is provided with an inlet opening 77 communicating with the passageway 73 leading from the rear end of the supply pipe 71 and from said inlet opening 77 a passageway 78 leads through the crank shaft to the two rearmost connecting rod bearings as shown in Figure I.

The crank shaft bearing 41 is provided with an inlet opening 79 which registers with the centrally disposed passageway 73 and from said inlet opening 79, passageways 80 and 81 extend forwardly and rearwardly respectively to the two connecting rod bearings adjacent the crank shaft bearings 40 and 41. The front and rear and intermediate eccentric shaft bearings are supplied with oil in a manner which will presently be described. The crank shaft bearings are each provided with a groove or recess 82 as shown in Figure IV, and said grooves receive the oil discharged from the end and intermediate leads 73 and from a passageway 83 leading through the bearing 40 from the passageway 80. Extending from each of said grooves or recesses 82 are outwardly extending passageways 84 leading to the

front, rear and intermediate eccentric shaft bearings, said passageways being clearly indicated in Figure IV. Leading from the groove 82 of the crank shaft bearing 40 is a by-pass 85 controlled by a spring pressed valve 86, the stem of which projects into a chamber 87 and is guided by a removable cover 88, said chamber having a diagonally disposed outlet passageway 89 for directing the excess lubricating material upon the drive chain 46 and other parts of the driving mechanism. It will be understood that the valve 86 will not be opened until the normal pressure in the system is exceeded, as when the pump is being driven above a predetermined rate of speed.

The rear end of the crank shaft is provided with a collar 90 for directing the excess oil from the bearing 34 into the oil groove 91 which is adapted to feed the oil downwardly through the discharge pipe 92 into the bottom of the crank case. By means of the pump 51, oil is forced through the three leads 73 extending from the supply pipe 71 and it will thus be seen that the oil is forced under pressure to the end and intermediate bearings of the crank shaft from whence it is forced to the connecting rod bearings and to the eccentric shaft bearings as well, and that although there is only one relief valve provided, the pressure is the same at the centers and ends of the crank and eccentric shafts, regardless of the fact that the oil feeding passageways for the several portions of the driving mechanism are not directly connected.

An oil sump 93 is positioned between the crank shaft bearings 40 and 41 beneath the sprocket chains 46 and 59 to supply oil to the latter, the oil being supplied to the sump by the overflow from the adjacent bearings of the crank shaft and other parts of the mechanism.

While I have shown and described in considerable detail certain specific embodiments of my invention, it is to be understood that this showing and description is illustrative only and for the purpose of rendering the invention more clear, and that I do not regard the invention as limited to the details of construction illustrated or described except in so far as I have included such limitations within the following claims, in which it is my intention to claim all novelty inherent in the invention, broadly as well as specifically.

What I claim as new and desire to secure by Letters Patent, is:—

1. In an explosive engine, a crank case, a crank shaft journaled therein, work performing shafts disposed upon the opposite sides of said crank shaft, and driving means extending in opposite directions from the crank shaft intermediate its ends and opera-

tively connected with said work performing shafts.

2. In an explosive engine, a crank case, a crank shaft journaled therein, work performing shafts disposed upon the opposite sides of said crank shaft substantially parallel therewith, sprockets formed upon the crank shaft intermediate its ends, and driving chains engaging said sprockets and operatively connected with said work performing shafts.

3. In an explosive engine, a crank case, cylinders disposed upon the crank case and provided with intake and exhaust ports, pistons within the cylinders, a crank shaft journaled in said crank case and operatively connected with said pistons, valves for controlling said ports, an eccentric shaft operatively connected with said valves, driving means connecting said shafts adjacent their centers, a work performing shaft journaled in the crank case, and driving means extending from the crank shaft intermediate its ends and connected with said work performing shaft.

4. In an explosive engine, a crank case, cylinders disposed thereon and having intake and exhaust ports, pistons within the cylinders, a crank shaft journaled in said crank case and operatively connected with said pistons, valves for controlling said intake and exhaust ports, an eccentric shaft operatively connected with said valves, driving means connecting said shafts adjacent the center of the engine, and a work performing shaft operatively connected with said crank shaft adjacent the center of the engine.

5. In an explosive engine, a crank casing, a crank shaft journaled therein, an eccentric shaft journaled in the casing, a chain drive connecting said shafts within the casing, and a removable oil sump disposed within the casing through which said chain is adapted to travel.

6. In an explosive engine, a crank casing, a crank shaft journaled therein, an eccentric shaft journaled in the casing, driving means connecting said shafts within the casing, and a removable oil sump within the casing in which said driving mechanism is adapted to travel.

7. In an explosive engine, a crank casing, cylinders carried by the casing provided with intake and exhaust ports, pistons within the cylinders, valves for controlling said ports, a crank shaft journaled in the casing and operatively connected with said pistons and valves, said crank shaft having passageways therein leading to its several bearings and each communicating with passageways formed in the walls of the casing, means for forcing lubricating material through the passageways in said casing walls to said

- crank shaft, and a spring pressed outlet valve in one of said casing passageways.
8. In an explosive engine, a crank casing having lubricating passageways formed therein, cylinders carried by the casing provided with intake and exhaust ports, pistons within the cylinders, valves for controlling said ports, a crank shaft journaled in the casing and operatively connected with said pistons, said crank shaft having passageways therein leading to its several bearings and communicating with the first mentioned passageways, an eccentric shaft journaled in the casing adapted to be driven by the crank shaft and operatively connected with said valves, lubricating passageways extending from the passageways in the crank shaft to the bearings of the eccentric shaft, means for forcing lubricant through the first mentioned passageways to the bearings of the said crank shaft and thence to the bearings of the eccentric shaft, and a spring pressed outlet valve in one of said passageways.
9. In an explosive engine, a crank casing having lubricating passageways formed therein, cylinders carried by the casing provided with intake and exhaust ports, pistons within the cylinders, valves for controlling said ports, a crank shaft journaled in the casing and operatively connected with said pistons, said crank shaft having passageways therein leading to its several bearings and communicating with the first mentioned passageways, an eccentric shaft journaled in the casing and operatively connected with said valves, driving means connecting said shafts at their centers, means for forcing lubricating material through said passageways to the bearings of said shafts, and a spring pressed outlet valve controlling an outlet passageway leading from said crank shaft and located to discharge lubricating material upon said driving mechanism when the valve is open.
- 45 10. In an explosive engine, a crank casing having lubricating passageways formed therein, a crank shaft journaled in the casing and having lubricating passageways therein leading to its several bearings and communicating with the first mentioned passageways, an eccentric shaft journaled in the casing, lubricating passageways extending from the passageways in said crank shaft to the bearings of said eccentric shaft, driving mechanism connecting said shafts

at their centers, means for forcing lubricating material through said passageways to said bearings, and a spring pressed valve controlling an outlet passageway leading from one of said bearings, said outlet passageway being located to discharge lubricating material upon said driving mechanism when the valve is open.

11. In an explosive engine, a crank casing having bearings formed therein, a crank shaft journaled in said bearings, an eccentric shaft journaled in the crank case, driving means connecting said shafts at their centers, lubricating passageways formed in the walls of the casing and leading to said crank and eccentric shaft bearings, means for forcing lubricating material through said passageways to each of said bearings, and a spring pressed valve closing an outlet passageway leading from one of the bearings, said outlet passageway being located to discharge lubricating material upon the driving mechanism when the valve is open.

12. In an explosive engine, a crank case, a crank shaft journaled therein, an eccentric shaft journaled in the casing, driving means connecting said shafts at their centers, lubricating passageways formed in the walls of the crank casing and leading to said crank and eccentric shaft bearings, an oil sump removably mounted within the casing beneath said driving means, means for forcing lubricating material through said passageways to each of said bearings, and a spring pressed valve controlling an outlet passageway leading from one of said bearings, said outlet passageway being located to discharge lubricating material upon said driving mechanism and within said sump.

13. In an explosive engine, a crank casing, a crank shaft journaled therein, an eccentric shaft journaled within the casing, driving means connecting said shafts within the casing, lubricating passageways leading to the bearings of said shafts, means for forcing lubricating material through said passageways, and a spring pressed valve controlling an outlet passageway leading from one of the bearings and located to discharge the excess lubricating material upon said driving means.

In testimony whereof, I affix my signature.

EDWARD H. BELDEN.
